UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE-CASTING BOX.

1,223,026.

Specification of Letters Patent. Patented Apr. 17, 1917.

Application filed October 12, 1914. Serial No. 886,215.

To all whom it may concern:

Be it known that I, HENRY F. BECHMAN, a citizen of the United States, residing at Battle Creek, in the county of Calhoun and State of Michigan, have invented certain new and useful Improvements in Stereotype-Plate-Casting Boxes; and I hereby declare that the following is a full, clear, and exact description thereof, reference being had to the accompanying drawings, which form part of this specification.

This invention relates to stereotype casting boxes and has particular reference to boxes for casting tubular stereotype plates of the type shown in my Patent No. 945,678 of January 4, 1910 for example; and the object of the present invention is to improve and simplify the construction of such boxes, increase their efficiency, and obviate some of the trouble which has been experienced with previously known boxes of this character.

I will explain the invention in detail with reference to the accompanying drawings which illustrate a practical casting box embodying the invention, and the features and combinations of parts for which protection is desired will be set forth in the claims following the description.

In said drawings:

80 Figure 1 is a side elevation of the casting box closed ready for casting a plate.

Fig. 2 is a top plan view of Fig. 1.

Fig. 3 is a side elevation showing the cope opened and the core partly lowered.

85 Fig. 4 is a detail side view of part of Fig. 3 showing the core almost in closed position.

Fig. 5 is a front elevation of Fig. 1.

Fig. 6 is a view showing the core lowered into position for removal of a plate therefrom.

As shown in the drawings the box comprises a base A to which are secured side frames B, B upon which are rigidly mounted in vertical position a drag C that is provided on its front face with a semi-cylindric recess and with a vertical rib c to engage the matrix when the latter is inserted in the box. The specific matrix retaining devices form no part of the present invention and may be of any suitable kind.

To the drag C is hinged a cope D, the hinges being indicated at d, so that the cope can swing horizontally to and from the drag. The cope has a semi-cylindric recess in its inner face and when the drag is

closed as indicated in Fig. 2 the opposed recesses in the drag and cope form a true cylindric chamber whose diameter equals the exterior diameter of the plate to be cast plus the thickness of the matrix.

The core E in the present invention has a lower portion e which comes below the drag and cope and is provided with trunnions e' on opposite sides, which are pivoted in suitable bearings in the side frames B, B, so that said core can be swung in a vertical plane. The core has an upper cylindric portion e² whose diameter substantially conforms to the desired internal diameter of the plate to be cast and is therefore less in diameter than the diameter of the chamber between the cope and drag.

This cylindric part e² is preferably slightly longer than the cope and drag and extends above the same and is preferably tapered off on the front side, as indicated at e³, to form a pouring mouth. The core is also provided at the lower end of the part e² with an annular flange e⁴ which closes the bottom of the casting space when the parts are in position for casting a plate, as indicated in Figs. 1 and 2.

The core is also provided with a rib e⁵ which co-acts with the part c on the drag to hold a matrix during the casting operation in the usual manner.

The cope may be provided with a handle d' and with a projecting lug d² adjacent its hinged end which when the cope is thrown open will contact with an opposed projection c² on the drag and limit the opening of the cope.

The cope is provided with a pin or roller Z on its free side which is adapted to be engaged by a slotted cam W pivoted upon a pin or stud Y attached to the side of the drag, see Figs. 1 and 3, and said cam plate may be operated by means of a handle w' which when the cope is opened contacts with and rests upon a stop pin X on the drag so that the mouth of the cam slot W is in position to engage the pin Z when the cope is closed. The slot in cam W is so shaped that the pin Z on the cope will enter its mouth and start handle w' forward, and the operator by then drawing handle w' forward causes the cam W to draw the cope closely against the drag and lock it securely in closed position as indicated in Fig. 1. When it is desired to open the cope the op-

erator pushes handle w' backward causing the slot in cam W to start the cope open, in a forcible manner, the cope being afterward fully opened by handle d' .

5 It will be observed that the core trunnions e' are not at diametrically opposite points on the core, but are located off the center line thereof so that when the cope is opened the core will naturally tend to tilt forward on 10 the trunnions and away from the drag, by gravity; which tilting action will be enhanced by the weight of the cast plate upon the part e^2 of the core. This eccentric location of the trunnions therefore causes the 15 core to automatically start out of the box, by gravity, when the cope is thrown open. A counterbalancing weight F is attached to the lower end of the part e of the core below the trunnions, as shown, to prevent too sudden 20 dropping of the core, and to also practically counterbalance the cylindrical part e^2 of the core, and enable it to be easily returned to casting position.

When a cast plate (not shown) is on the 25 core the weight of the plate overbalances the weight F and would cause the core E to drop too rapidly to open position; and to prevent injury by any such action and at the same time permit the core to drop by gravity with 30 the cast plate to the position shown in Fig. 6, I preferably employ an air cushion, comprising a cylinder L in which is a piston K attached to a piston rod I. The cylinder L is preferably fastened to the side of the drag 35 and closed at top, and the piston rod I extends downwardly and is provided with rack teeth i on its lower end which teeth are engaged by a segment H that is rigidly fastened to one of the trunnions e' of the core, 40 as shown. The rack I may be guided beside the segment H in a grooved roller J rotatably mounted upon a stud j on one of the frames B, as shown. When the core tilts 45 forwardly the segment H causes piston K to rise in the air cylinder, and the ascent of the latter being resisted and cushioned by the air in the cylinder, the core will descend when it is loaded with the cast plate almost to the position indicated in Fig. 6, and with- 50 out shock.

Attached to the other trunnion of the core is a cam plate G which has a peculiarly shaped cam slot g that is engaged by a roller M on a stud N attached to a lever O pivoted 55 at o to one of the side frames B. The slot g is so shaped that when the core is raised to almost vertical position the roller M will enter one of the ends of the cam slot and the operator by then depressing lever O will 60 cause roller M to enter this end of the cam slot and hold the core raised in approximately closed position against the drag, see Fig. 1.

After the casting operation the cope is 65 opened, and by lifting lever O the core is

started outward and its upper end will descend by gravity, as stated, until the roller M approaches the other end of the slot g , and then by depressing lever O the roller M is caused to forcibly enter such end of the slot 70 g , see Fig. 6, and will hold the core in lowered position for the removal of the plate; when the plate has been removed and it is desired to return the core the lever O may be slightly lifted and then the core 75 will by the action of counterbalance before described automatically return to approximately vertical position, see Fig. 4, at which point roller M will engage the other end of the slot g as described.

The lever O is provided with a dog P which is pivoted to the lever and is adapted to engage a catch bolt Q projected by a spring S in a box R attached to the frame or base below the lever O. When the dog 80 P engages bolt Q as shown in Fig. 4, it will prevent core E from falling or moving into casting position until after the matrix has been adjusted around the core and in the drag. Then the operator should disengage 85 dog P from the core by kicking the dog outward with his foot, the dog being provided with a pin p on its lower end for this purpose; then the core can be moved farther 90 inward and the cope can be closed as indicated in Fig. 2. If the operator should forget to disengage the dog P from the catch 95 Q and close the cope onto the core while the parts are in the position shown in Fig. 4, the spring S would yield and allow the lever O 100 to descend and the cope to be closed without injury to the cope or the core.

In such boxes it is desirable to cool the core during the casting operations, when a 105 number of plates are being cast; for this purpose, in the machine shown in the drawings, the core is made hollow and is provided with internal pipes E', E². One of these pipes E communicates at bottom with a passage e^8 leading through one of the trunnions e' and connected to an elbow T at the outer end of the trunnion. The other pipe E² communicates with a passage e^7 leading through the other trunnion and connected with an elbow T'. The elbow T is connected 110 by a hose section U with an elbow or union V attached to one of the side frames B, and which may in turn be connected with a water supply pipe in any suitable manner. The elbow T' is connected by a hose section U' with an elbow V' attached to the opposite frame B, and which may be connected by a pipe to an outlet. The water passes through the connections V, U, T, and pipe E' into the core, thence it passes to the top and escapes through the pipe E² and connections T', U', V'. The pipe E' is preferably made 115 slightly longer than pipe E² so that the drain will be slightly below the inlet as set forth in my aforesaid patent. The trun- 120 125 130

nions e' being placed to one side of the axis of the core will allow the latter to swing outwardly without the flange e^4 striking the lower portion of the drag. The slot in cam 5 G is so shaped that it will securely hold the core E in either raised or lowered position.

Operation.

When casting a plate the cope is swung open, and the core raised to the position indicated in Fig. 4; the ascent of the core being cushioned by the piston K in air cylinder L, which is preferably made double acting so that both the raising and lowering of 10 the core is cushioned thereby. After the core is raised the matrix (not shown) is adjusted around the core with its ends inserted into the recess in the drag at opposite sides of the rib c; then the dog P should be disengaged from catch Q, and the cope closed and locked by the cam W as shown in Figs. 1 and 2. The box is then filled with metal poured in at the top of the core E. During 15 the casting operation the core is kept cool by the water circulated therethrough. After casting the plate the cope is released and partially opened by throwing the handle w' 20 backward, then the cope is swung open to the position shown in Fig. 3; the core then tilts forward and drops under the weight of the cast plate nearly to the position shown in Fig. 6; the dropping of the plate-laden core being cushioned by the piston K in cylinder L. The operator then depresses lever 25 30 O which lowers the core to the position shown in Fig. 6 and locks it in that position, and the cast plate is removed by slipping it endwise off the part e^2 .

What I claim is:

1. In a stereotype casting apparatus the combination of a cope and a drag adapted to surround a core, with a hollow core mounted on hollow trunnions, a water inlet connection with one hollow trunnion, and a water 40 outlet connection with the other hollow trunnion.
2. In a stereotype casting apparatus the combination of a cope and a drag adapted to surround a core, with a hollow core mounted 45 on hollow trunnions, an inlet and a drain pipe within the core, water inlet connections with one trunnion, and a water outlet connection with the other trunnion, substantially as described.
3. In a stereotype casting apparatus the combination of a cope and a drag adapted to surround a core, with a hollow core mounted 50 on hollow trunnions, an inlet and a drain pipe within the core, a flexible water inlet connection with one hollow trunnion, and a flexible water outlet connection with the other hollow trunnion.
4. In a casting box the combination with 55 a tiltable core; of a cam plate connected with the core, and a lever engaging the cam

plate to hold the core in either raised or lowered position.

5. In a casting box, the combination of a tiltable core adapted to tilt by gravity; with means to hold the core in near but out of 70 casting position.

6. In a casting box, the combination of a tiltable core having trunnions at one side of its axial line to cause the core to tilt by gravity; with means to lock the core in 75 raised or lowered position, and means for cushioning the descent of the core.

7. In a casting box, the combination of a tiltable core having trunnions at one side of its axial line to cause it to tilt by gravity; 80 with a cam plate connected with the core, a lever engaging the cam plate to hold the core in raised or lowered position, and an air cushion for arresting the descent of the core.

8. In combination, a drag, a cope, a tiltable core having trunnions on which said core is pivotally mounted, a cam plate attached to one trunnion having a cam slot, and a lever engaging said cam slot and 90 adapted to hold the core in elevated or lowered position.

9. In combination, a drag, a cope, a tiltable core having trunnions on which it is pivotally mounted, a cam plate attached to 95 the trunnion having a cam slot, a lever engaging said cam slot to hold the core in elevated or lowered position, a dog pivoted to said lever, and a catch adapted to engage said dog and hold the core out of casting position.

10. In combination, a drag, a cope, a tiltable core, and air compression means for regulating the lowering and raising of the core.

11. In combination, a drag, a cope, a tiltable pivotally mounted core, an air cylinder, 105 a piston therein, and operative connections between said piston and the core.

12. In combination, a drag, a cope, a tiltable core pivotally mounted on trunnions, 110 an air cylinder, a piston therein, a toothed rack connected with said piston, and a segment connected to the core and engaging said rack.

13. In combination, a drag, a cope, a tilting core, a pivoted lever to hold the core in substantially closed position, and yieldable means to lock the lever when the core is raised.

14. In combination, a drag, a cope, a tilting core, a pivoted lever to hold the core in substantially closed position, a dog pivoted on the lever, and a spring pressed bolt adapted to be engaged by said dog to hold the core out of casting position.

15. In combination, a drag, a cope, a tiltable core, means to cushion the movement of the core, a lever adapted to hold the core in raised or lowered position, and means for yieldingly locking said lever.

16. In combination, a drag, a cope, a tilt-
ing core having a cam plate, a pivoted lever
engaging the cam plate to hold the core in
substantially closed position, and yieldable
means to lock the lever when the core is
raised.

17. In combination, a drag, a cope, a tilt-
ing core having a cam plate, a pivoted lever
engaging the cam plate to hold the core in
substantially closed position, a dog pivoted
on the lever, and a spring pressed bolt
adapted to be engaged by said dog to hold
the core in raised position.

18. In combination, a drag, a cope, a tilt-
able core pivotally mounted on trunnions,
means to cushion the descent of the core, a
slotted cam plate attached to the core, a lever
having a pin engaging the slot in said cam
plate to hold the core in raised or lowered
position, and means for yieldingly locking
said lever to hold the core in raised position.

19. In combination, a drag, a cope, a tilt-
able core, an air cylinder, a piston therein
and operative connections between the pis-
ton and the core; with a slotted cam plate
attached to the core, a lever having a pin en-
gaging the slot in said cam plate to hold the
core in raised or lowered position, and means
for yieldingly locking said lever.

20. In combination, a drag, a cope, a tilt-
able core, an air cushion device, with a cam
plate attached to the core, a lever engaging
the said cam plate to hold the core in raised
or lowered position, and means for yield-
ingly locking said lever.

21. In combination, a drag, a cope, a tilt-

able core pivotally mounted on trunnions,
an air cylinder, a piston therein, a toothed
rack connected with said piston, and a seg-
ment connected to one of the core trunnions 40
engaging said rack; with a cam plate at-
tached to one of the trunnions of the core,
a lever engaging the said cam plate to hold
the core in raised or lowered position, and a
dog and co-acting spring bolt for yieldingly 45
locking said lever to hold the core in raised
position.

22. In a casting box, a cope, a drag and a
tiltable core coöperating with the cope and
drag to form a casting chamber, said core 50
having trunnions located at one side of its
axial line to cause the core to tilt by gravity
when the box is opened.

23. In a casting box, the combination of a
drag, a cope, and a tiltable core having axi- 55
ally aligned trunnions at one side of its axis
to cause the core to tilt by gravity when
loaded with a cast plate and the box is
opened.

24. In a casting box, the combination of 60
a cope, a drag, and a tiltable core adapted to
tilt by gravity when the box is opened; with
means to hold the core in raised or lowered
position, and means for cushioning the
gravital descent of the core.

In testimony that I claim the foregoing as
my own, I affix my signature in presence of
two witnesses.

HENRY F. BECHMAN.
